CLAIM

The ornamental design for a tampon applicator, as shown and described.

DESCRIPTION

FIG. 1 is a perspective view of a tampon applicator showing the new design;

FIG. 2 is a side elevation view thereof (the opposite side elevation view is identical and has thus been omitted);

FIG. 3 is a top elevation view thereof (the bottom elevation view is identical and has thus been omitted);

FIG. 4 is an end view thereof; and,

FIG. 5 is an end view thereof, opposite that shown in FIG. 4.

The broken lines shown in FIGS. 1 and 2 are for illustrative purposes only and form no part of the claimed design.
